BOX LINING

James W. Trew, Gettysburg, Pa., assignor to Rice, Trew & Rice Co. Inc., Biglerville, Pa., a corporation of Pennsylvania

Application July 19, 1934, Serial No. 736,112

4 Claims. (Cl. 217—3)

This invention relates to a box lining and particularly to a lining for a box wherein the side walls are substantially in right angular relation, and it is an object of the invention to provide a lining of this kind which not only serves as a protection for the box content but eliminates the necessity of applying a lid or cover to the filled container.

It is also an object of the invention to provide a lining for a box which when applied offers no undue hinderance or obstruction to the desired air circulation within the container and wherein the lining for a single box or container comprises two duplicate sections whereby the application of the lining is materially facilitated without requiring any special skill on the part of the workman.

The invention consists in the details of construction and in the combination and arrangement of the several parts of my improved box lining whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in perspective illustrating a lining constructed in accordance with an embodiment of my invention and in applied position, the flaps of the lining being in open position and somewhat distorted for clarity in disclosure;

Figure 2 is a view in perspective of a completed package with my improved lining applied;

Figure 3 is a transverse sectional view taken through the package as illustrated in Figure 2, the box content being indicated by broken lines;

Figure 4 is a view in perspective of one of the lining sections as herein employed and in the operative assembly;

Figure 5 is a view of the blank from which a lining section is produced;

Figure 6 is a view in perspective illustrating a box having applied thereto a lining constructed in accordance with a further embodiment of my invention;

Figure 7 is a transverse sectional view of the structure as illustrated in Figure 6;

Figure 8 is a view in plan of the blank from which is produced one of the sections of the lining as illustrated in Figure 6;

Figure 9 is a view in transverse vertical section taken through a box or crate having applied thereto a lining constructed in accordance with an additional embodiment of my invention, the box or crate content being indicated by broken lines;

Figure 10 is a view in top plan of the assembly as illustrated in Figure 9 with the box or crate content omitted;

Figure 11 is a view in perspective of a lining section constructed in accordance with an embodiment of the invention as illustrated in Figures 9 and 10 unapplied;

Figure 12 is a view in plan of the blank from which is produced a lining section as illustrated in Figures 9, 10 and 11.

In the embodiment of my invention as particularly illustrated in Figures 1 to 5 inclusive, B denotes a box or crate of a conventional type wherein the end walls 1 and the side walls 2 are substantially at right angles and wherein each of the side walls terminates a slight distance above the bottom 3 of the box or crate to provide an opening 4 to facilitate air circulation through the box or crate content for the purpose of ventilation. This box or crate is of a standard design and forms no part of my invention.

My improved lining for the box or crate B as herein disclosed comprises two substantially duplicate sections L each of which is produced from an initially flat blank of paper board or other material possessing the desired weight and quality. As particularly illustrated in Figure 5 of the drawings the blank for the lining section L comprises a panel 5 of dimensions substantially identical with the dimensions of a side wall 2 of the box or crate B and against which side wall the panel 5 has close contact from within the box or crate B when the lining section 5 is in applied or working position.

The ends of the panel 5 are continued by the end panels 6 which are separated from the ends of the panel 5 by the score lines 7 disposed transversely of the panel 5 and upon which the panels 6 readily fold so as to have close contact with the inner faces of the end walls 1 of the box or crate B when the lining section L is applied.

These panels 6 have end portions 8 extending below the lower marginal portion of the panel 5 for direct contact with the bottom wall 3 of the box or crate B so that the lower marginal portion of the panel 5 will be spaced from the bottom 3 of the box or crate B a distance substantially equal to the height of the adjacent opening 4 so that the applied lining section will offer no

hindrance or obstruction to the desired circulation of air through the content of the box or crate B for the purpose of ventilation which is particularly desirable when the box or crate B is being employed in the packing and shipping of fruits, vegetables and the like.

Each of the end panels 6 is of a length substantially equal to one-half of the length of an end wall 1 of the box or crate B as is particularly illustrated in Figures 1, 2 and 3 so that when the two lining sections are applied the inner faces of the end and side walls of the box or crate B are effectively covered. The upper marginal portions of the end panels 6 are separated by the score lines 9 from the locking flaps 10. These flaps 10 are adapted to be folded along the score lines 9 to be disposed inwardly of the box or crate B above the content of the box or crate B and which content readily holds said flaps in desired working or effective position. The corner portion of each of the flaps 10 close to the outer edge of the adjacent end panel 6 is provided with an obliquely disposed slot 11 extending from a point substantially immediately adjacent to the score line 9 to a point in relatively close proximity to the side edge of the flap 10 which is substantially in continuity with the outer edge of the adjacent end panel 6.

The panel 5 has its upper margin defined by a score line 12 coplanar with the score lines 9 and which score line 12 separates the panel 5 from a top closing flap 14. This flap 14 is adapted to swing inwardly of the box or crate above the previously positioned flaps 10. The outer free corner portions 15 of this flap 14 are readily insertable through the slots 11 whereby the flap 14 is held in closed position as illustrated in Figures 2, 3 and 4.

As is clearly disclosed in the accompanying drawings, the end portion of each of the flaps 14 is of a length less than the intermediate or major portion of the flap. This is done so that when the lining section has been applied the desired interlocking of the outer corner portions of the flap 14 with the end panels 10 is materially facilitated.

With my improved lining applied it is to be noted, as illustrated in Figures 2 and 3, that the normally open top of the box or crate B is effectively closed and in a manner to assure desired protection of the content and, therefore, with the use of my improved lining it is not necessary that the conventional lid or cover be applied to the box or crate although of course this can be done if desired. It is also to be stated that my improved lining is particularly adaptable for use in connection with packages wherein the content of the box or crate does not materially extend above the upper marginal portions of the side walls of the box or crate.

In the embodiment of the invention as illustrated in Figures 6, 7 and 8, the lining section L' is of substantially the same construction as each of the lining sections L hereinbefore referred to except that the lower edges of the end panels 6' are substantially flush with the lower edge of the side panel 5' or, in other words, the end panels 6' as well as the panel 5' are of a height substantially equal to the height of the adjacent side wall of the box or crate in which the lining section L' is applied.

The upper inner corner portion of each of the end panels 6' has cut therefrom a tab 16 which, when the end panels 6' are swung inwardly on the score lines 7', remain substantially coplanar

with the panel 5' so that said tab 16 will extend beyond the opposite ends of the panel 5' to contact from above with the upper marginal portion of a side wall 2' of the box or crate B' or to slip between the upper marginal portion of a side wall 2' and the upper portion of the adjacent vertical edge of an end wall 1' as is illustrated in Figures 6 and 7 of the drawings. These tabs 16 serve to provide support for an applied lining section L' with the lower margin of the panel 5' of such section spaced above the bottom 3' of the box or crate B' so that no hindrance or obstruction will be offered to the opening 4' to allow for the desired ventilation of the content of the box or crate B'. 15

In Figures 9, 10, 11 and 12 I disclose an embodiment of my invention which can be employed with equal facility within a conventional box or crate or in connection with a box or crate comprising in its structure the corner bracing 20 posts P. The lining as comprised in this form of my invention also embodies two substantially duplicate sections L'', each of which is produced from an initially flat blank of paper board or other material possessing the desired weight and 25 quality. Each of these sections L'' has a panel 5'' of dimensions substantially identical with the dimensions of a side wall 2'' of the box or crate B'' and against which side wall the panel 5'' has close contact from within. 30

The ends of the panel 5'' are continued by the end panels 6'' which are separated from the ends of the panel 5'' by the score lines 7'' and upon which the panels 6'' readily fold in order to have desired close contact with the inner faces 35 of the end walls 1'' of the box or crate B''. The panels 6'' have portions 8'' extending below the lower marginal portion of the panel 5'' for direct contact with the bottom wall 3'' of the box or crate B'' so that the lower marginal portion 40 of the panel 5'' will be spaced from the bottom wall 3'' of the box or crate B'' a distance substantially equal to the height of the adjacent opening 4'' at the lower portion of the side of the box so that the applied lining section L'' 45 will offer no hindrance or obstruction to air circulation through the box or crate content.

The distance between the score lines 7'' is substantially equal to the distance between the 50 end walls 1'' of the conventional box. However, when corner posts P are employed it is important that provision be made to allow the extremities of the panel 5'' to sufficiently fold or flex to compensate for such corner posts. For this purpose 55 I provide the panel 5'' at the required distance inwardly of a score line 7'' with the supplemental score lines 7^a extending entirely across the panel 5''. These score lines 7^a permit desired flexure therealong when the lining section L'' is being 60 applied when the portion of the panel 5'' outwardly thereof contacts with a corner post P.

From the foregoing description it is thought to be obvious that a box lining constructed in accordance with my invention is particularly well 65 adapted for use by reason of the convenience and facility with which it may be assembled and employed, and it will also be obvious that my invention is susceptible of some change and modification without departing from the principles and 70 spirit thereof and for this reason I do not wish to be understood as limiting myself to the precise arrangement and formation of the several parts herein shown in carrying out my invention in practice except as hereinafter claimed. 75

I claim:—

1. A lining for a box comprising two substantially duplicate sections, each of said sections comprising a panel for contact from within with a side wall of the box and overlying substantially the entire area of said side wall, end panels carried by the side panel for close contact from within with the end walls of the box, each of said end panels overlying substantially one-half the area of a side wall, a top closing flap carried by the upper margin of the side panel, said flap to extend inwardly of the box over the box content and covering substantially one-half of the area of the top of the box, and end flaps carried by the upper marginal portions of the end panels to extend inwardly of the box over the box content and beneath the closing flap, the outer free corner portions of the closing flap and the inner corners of the end flaps adjacent the free ends of the end panels having coacting means for holding the closing flap in working position.

2. A lining for a box comprising two substantially duplicate sections, each of said sections comprising a panel for contact from within with a side wall of the box and overlying substantially the entire area of said side wall, end panels carried by the side panel for close contact from within with the end walls of the box, each of said end panels overlying substantially one-half the area of a side wall, a top closing flap carried by the upper margin of the side panel, said flap to extend inwardly of the box over the box content and covering substantially one-half of the area of the top of the box, and end flaps carried by the upper marginal portions of the end panels to extend inwardly of the box over the box content and beneath the closing flap, the outer free corner portions of the closing flap and the inner corners of the end flaps adjacent the free ends of the end panels being provided with slots, the outer corner portions of the closing flap passing through the slots in a direction inwardly of the box to hold the closing flap in working position, the end portions of the closing flap being of a length less than the intermediate major portion of the closing flap.

3. A lining for a box comprising two substantially duplicate sections, each of said sections comprising a panel for contact from within with a side wall of the box and overlying substantially the entire area of said side wall, end panels carried by the side panel for close contact from within with the end walls of the box, each of said end panels overlying substantially one-half the area of a side wall, a top closing flap carried by the upper margin of the side panel, said flap to extend inwardly of the box over the box content and covering substantially one-half of the area of the top of the box, and end flaps carried by the upper marginal portions of the end panels to extend inwardly of the box over the box content and beneath the closing flap, the outer free corner portions of the closing flap and the inner corners of the end flaps adjacent the free ends of the end panels having coacting means for holding the closing flap in working position, and means carried by the side panel for coaction with the box to hold the lower marginal portion of the side panel spaced from the bottom of the box.

4. A lining for a box comprising two substantially duplicate sections, each of said sections comprising a panel for contact from within with a side wall of the box and overlying substantially the entire area of said side wall, end panels carried by the side panel for close contact from within with the end walls of the box, each of said end panels overlying substantially one-half the area of a side wall, a top closing flap carried by the upper margin of the side panel, said flap to extend inwardly of the box over the box content and covering substantially one-half of the area of the top of the box, end flaps carried by the upper marginal portions of the end panels to extend inwardly of the box over the box content and beneath the closing flap, the outer free corner portions of the closing flap and the inner corners of the end flaps adjacent the free ends of the end panels having coacting means for holding the closing flap in working position, and means carried by the side panel for coaction with the box to hold the lower marginal portion of the side panel spaced from the bottom of the box.

JAMES W. TREW
